(57) **CLAIM**

The ornamental design for an industrial instrument with circular touch screen, as shown and described.

DESCRIPTION

FIG. 1 is a front perspective view of an industrial instrument with circular touch screen according to a first embodiment of my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is rear perspective view thereof;

FIG. 9 is a front perspective view thereof in an environment of use;

FIG. 10 is a front perspective view of an industrial instrument with circular touch screen according to a second embodiment of my new design;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is rear perspective view thereof;

FIG. 18 is a front perspective view of an industrial instrument with circular touch screen according to a third embodiment of my new design;

FIG. 19 is a front view thereof;

FIG. 20 is a rear view thereof;

FIG. 21 is a right side view thereof;

FIG. 22 is a left side view thereof;

FIG. 23 is a top view thereof;

FIG. 24 is a bottom view thereof; and,

FIG. 25 is rear perspective view thereof.

Broken lines are environmental only and form no part of the claimed design.

The broken lines of even length depict portions of the industrial instrument with circular touch screen, as well as environment in FIG. 9, that form no part of the claimed design. The broken lines of uneven length represent the boundary of the claimed design that form no part of the claimed design.

1 Claim, 22 Drawing Sheets
